UNITED STATES PATENT OFFICE.

JAMES F. McELROY, OF ALBANY, NEW YORK, ASSIGNOR TO CONSOLIDATED CAR HEATING COMPANY, OF ALBANY, NEW YORK, A CORPORATION OF WEST VIRGINIA.

EXPANSIBLE CELL FOR THERMOSTATS.

No. 874,022.

Specification of Letters Patent.

Patented Dec. 17, 1907.

Application filed April 7, 1906. Serial No. 310,406.

To all whom it may concern:

Be it known that I, JAMES F. McELROY, a citizen of the United States, residing at Albany, in the county of Albany and State 5 of New York, have invented certain new and useful Improvements in Expansible Cells for Thermostats, of which the following specification and accompanying drawings illustrate the invention in a form which I now regard 10 as the best out of the various forms in which it may be embodied.

This invention relates to the construction of thermostatic cells used for steam traps and other purposes and its object is to avoid 15 the breakages to which such cells are subject.

Of the accompanying drawings: Figure 1 represents a section showing a steam trap of railway-car type provided with my improved form of cell, Fig. 2 represents a plan view of 20 the cell, Fig. 3 represents a plan view of a modified form of the cell, Fig. 4 represents a section of the latter, Fig. 5 represents a sectional view illustrating the action of the internal pressure in determining the proper 25 form for the cell.

The same reference characters indicate the same parts in all the views.

It has been the practice to make thermostatic cells for steam traps in the form of 30 flexible-walled chambers of flattened circular shape and to fill them with a liquid of low boiling-point, such as alcohol, the vapor pressure of which expands the walls of the cell when the latter is subjected to the heat 35 of steam passing through the trap, and this expansion causes a movement of the trap valve. The cell is commonly made by attaching together by their circular edges two dished diaphragms of sheet-brass or copper 40 to form a pressure-tight chamber containing the liquid, and the "expansion" of the cell under internal vapor-pressure is in reality a distortion caused by the effort of the cell to assume a shape of greater cubical capacity 45 than its normal shape, resulting in a separation of the middle portions of the opposed walls or diaphragms.

Heretofore the cells have given much trouble by breaking or cracking after comparatively short periods of use, and I have discovered the cause to consist in a disregard 50 of the proper principles in shaping the cell. Frequently the cells have been made with abrupt bends or folds in their movable walls,

and often they have possessed an approximately rectangular form in cross-section, giving a well-marked pivot or hinge-line at the corners, which would then constitute the outer margins of the flexible parts of the cell-walls. Whenever such bends or corners 60 exist, the metal will soon begin to crack at that place, and the cell be rendered useless. If breakage is to be avoided, there must be no abrupt bends or corners in that region of the flexible cell-wall which is subject to the 65 greatest bending movement during the expansion and contraction of the cell in the course of its operation.

In order to ascertain the proper cross-sectional form for the cell, I performed the 70 experiment of making a cell with very thin and very flexible metal walls, filling it with the usual liquid and sealing it, confining it between resistance pieces to substantially 75 duplicate its situation in a steam-trap, and then subjecting the cell to heat in order to produce an internal pressure. The result was that the outer or unconfined portions assumed a shape substantially circular in cross-sectional outline, as indicated in Fig. 5, 80 where 10 represents a cell supposed to have walls of perfect flexibility, and 11 12 the upper and lower resistance pieces. This action can be explained from the fact that the internal pressure, which is exerted radially in all directions, tends to impart the 85 circular form, namely that form which possesses the greatest area for any given circumference.

In putting the above principles into practice I make the actual cell, as shown in Figs. 1 and 2, for example, of the same cross-sectional outline in its marginal or unconfined part as a cell of perfect flexibility and corresponding dimensions would tend to assume 90 under internal pressure, namely an approximately circular outline. In Figs. 1 and 2, 10 is the cell composed of upper and lower circular dished diaphragms 13, 14, beaded and soldered together at their edges 100 15. 12 is the lower resistance piece or seat for the cell, fixed to the trap casing, and 11 is the upper resistance-piece constituting a follower attached to the stem of the trap valve 16. The resistance pieces may either rest in 105 the lowest hollows of the diaphragms as seen in Fig. 1 or the diaphragms, as shown in Figs. 3 and 4, may have raised flat central portions

17 for contact with the resistance pieces. In both cases it will be seen that the cross-sectional outline of the two diaphragm-margins taken together conforms substantially to the 5 greater or major arc of the circle.

The above-described diaphragms are free from permanent folds, corrugations or corners in the marginal portions subject to the greatest bending in operation, and the actual 10 flexure which takes place is distributed throughout a large area and not confined to any well-marked line or lines. Consequently premature breakage and cracking are practically eliminated.

15 What I claim as new and desire to secure by Letters Patent is:

1. A thermostatic cell for steam traps or other controllers comprising a sealed flexible metal casing of flattened form containing a 20 liquid and having walls with wide central seats on opposite sides for abutting the resistance pieces of the trap or other controller

and a marginal flexing portion free from abrupt bends and of substantially the same sectional outline which a corresponding wall 25 of perfect flexibility would tend to assume under the influence of internal pressure.

2. A sealed thermostatic cell containing a liquid of low boiling-point and having walls composed of two flexible metal diaphragms 30 free from abrupt bends in their flexing portions and connected by their edges, said diaphragms having substantially-flat central portions and having marginal portions which together conform substantially to the 35 major arc of a circle.

In testimony whereof I have hereunto set my hand in the presence of two subscribing witnesses, the 3rd day of April 1906.

JAMES F. McELROY.
